Michael Miller INVENTOR

UNITED STATES PATENT OFFICE.

MICHAEL MILLER, OF BRILLION, WISCONSIN.

FOLDING OR COLLAPSIBLE EGG-CASE.

No. 874,104.

Specification of Letters Patent.

Patented Dec. 17, 1907.

Application filed January 10, 1906. Serial No. 295,510.

To all whom it may concern:

Be it known that I, MICHAEL MILLER, a citizen of the United States, residing at Brillion, in the county of Calumet and State of Wisconsin, have invented a Folding or Collapsible Egg-Case.

This invention relates to improvements in collapsible crates adapted primarily for carrying eggs or the like.

The object of the invention is to provide a convenient and economical structure capable of being folded in a small space for shipping purposes.

Other objects and advantages will be hereinafter referred to and particularly pointed out in the claims.

In the drawings—Figure 1 is a longitudinal section of my improved box. Fig. 2 is a plan view of the same. Fig. 3 is a longitudinal section, showing the box folded. Fig. 4 is a cross-section showing the box folded. Fig. 5 is a perspective view of the box set up, the cover being partially broken away. Fig. 6 is a perspective view of the box folded. Fig. 7 is a detail plan view of one of the swinging catches used to lock the cover in place. Fig. 8 is a detail transverse section of the box showing the application of a swinging catch.

The letter B, indicates a bottom board, having end cleats b, b, and side cleats c, c', the former extending upwardly more than the latter. End sections E, E, are hinged to the end cleats b, b, as indicated at e, e, whereby the said ends may be folded inwardly. The edges of the sections E, E, abut against the upper edges of the end cleats, so that when said sections are in their raised position they are limited in their outward movement.

Side sections S, S, are hinged at P, P, to the side cleats c, c', the edges of the said sections and cleats abutting, for the same purpose described in connection with the end sections and cleats. The cleat c, extends upwardly beyond the plane of the top of the cleat c', to permit of the folding of the side sections in compact form as shown in Fig. 3.

The side sections are provided with end flanges D, to engage the outer sides of the end sections when the box is erected for use, and catches R, on said side sections serve to lock the end and side sections together.

On the inner side of the side sections, just below the top edges thereof, are flanges C, C, the outer ends of which abut against the inner sides of the end sections, and are sepa-

rated at a point near their centers to accommodate a partition H. A cover A, is supported on the flanges C, C, its top surface being slightly below the top edges of the side and end sections.

60

Several swinging catches K, are pivotally mounted on the top of the cover, adapted to lock the latter in position. Each swinging catch comprises a body portion k, a finger piece k', and a hooked end k'', formed with a seal opening M. The hooked ends k'', operate in slots j, formed in the side sections S, S, and engage pins L, extending across the slots. After the swinging catches are locked in position seals are passed through the openings 70 M, for obvious purposes.

To fold the box, the usual division strips &c. F, and G, are placed on the bottom B, together with the partition H, and cover A, then the end sections E, E, are folded inwardly, and side section S, on cleat c', is folded inwardly, and finally the companion side section S, is likewise folded, producing a neat and compact structure. To erect the box, the end and side sections are turned up, 80 the edge of the end sections being engaged by the ends of the side sections and the flanges thereon and the catches R, hold the sections together. The cover A, is now supported on the flanges and the swinging catches K, are 85 operated to engage the pins L.

Having thus described the invention; what is claimed and desired to be secured by Letters Patent, is

1. A folding box comprising a bottom having end and side cleats, end sections hinged to the inner edges of the end cleats, side sections hinged to the inner edges of the side cleats, flanges on the inner surfaces near the ends of the side sections, said flanges and the 95 abutting edges of the end sections and end cleats holding said end sections in vertical position, catches for securing the end and side sections together, horizontal flanges located on the inner faces of the side sections 100 below the top edges thereof, said horizontal flanges on each side section being spaced apart at their adjacent ends while the opposite ends of said flanges fit against the inner faces of the end sections, a partition fitting in the spaces formed by the horizontal flanges and resting on the bottom, a cover supported by the horizontal flanges, the upper surface of said cover being below the upper edges of the side and end sections, swinging catches 110

pivoted to the cover and adapted to pass through the slots and engage the pins therein to secure the cover in place.

2. A folding box comprising a bottom having hinged end and side sections, certain of said sections having slots and pins extending across said slots, means between the end and side sections for holding the sections together, flanges on selected sections and located below the top edges of the said sec-

tions, a cover supported on the flanges and fitting within the side and end sections, swinging catches on the upper surface of the cover and below the top edges of the end and side sections to engage the slots and the pins 15 therein to hold the cover in position.

MICHAEL MILLER.
